UNITED STATES PATENT OFFICE.

THOMAS M. FARLEY, OF BROOKLYN, NEW YORK.

DESIGN FOR A BEDSTEAD-HEAD.

SPECIFICATION forming part of Design No. 34,512, dated May 14, 1901.

Application filed April 12, 1901. Serial No. 55,555. Term of patent 3½ years.

To all whom it may concern:

Be it known that I, THOMAS M. FARLEY, a citizen of the United States, and a resident of the borough of Brooklyn, county of Kings, State of New York, have invented and produced a new and original Design for a Bedstead-Head, of which the following is a full, clear, and exact specification, reference being had to the accompanying drawing, forming part hereof.

The figure represented herewith is a front elevation of a bedstead-head, showing the design.

The leading feature of my design consists in having elliptical figures or pieces at the intersection of the vertical corner or side posts A' and the transverse rods B, which connect said posts, and also shields arranged

upon the rods B at the points where they are joined by the vertical rods C. The posts A' ²⁰ are surmounted by ornamental pieces A², connected by a horizontal bar B', parallel with the top rod B and connected to the central rod C by a connecting-piece bearing a shield.

Having now described my invention, what ²⁵ I claim as new, and desire to secure by Letters Patent, is—

The design for a bedstead-head as herein shown and described.

In witness whereof I have hereunto set my ³⁰ hand in presence of two witnesses.

THOMAS M. FARLEY.
